ELECTRIC IRON

Filed Dec. 9, 1935

UNITED STATES PATENT OFFICE

2,143,424

ELECTRIC IRON

Alfred C. Schmidt, Teaneck, and Charles W.
Bruger, Union City, N. J.

Application December 9, 1935, Serial No. 53,572

2 Claims. (Cl. 219—25)

This invention relates to improvements in electric sadirons or flatirons for use in the home or by tailors or the like, and it is the principal object of our invention to provide an electric iron having its heating surface and thus its smoothing surface greatly enlarged by the arrangement of rollers which are rotating in suitable chambers formed in the body of the flatiron, and which have their outer mantles or peripheries flush with the smoothing or bottom face of the iron and which are substantially conical in opposite directions.

Another object of our invention is the provision of an electric flatiron equipped with means, such as for instance rollers, for greatly facilitating its operation notwithstanding its somewhat increased weight, and which are so closely arranged to the walls of their chambers as to present a nearly uninterrupted surface with the bottom of the iron.

Still another object of our invention is the provision of an electric flatiron, the rollers of which are arranged in convenient numbers and sizes, parallel to one another or in staggered relation allowing a ready operation of the iron across a fabric to be smoothed in all directions by a suitable handling of the iron.

A further object of our invention is the provision of an electric iron which will dispense a considerably greater amount of heat than the commonly used irons by virtue of the increase in the ironing surface by the rollers and the ready distribution of the heat from the interior through the chambers opening towards the bottom of the iron, and the increase in the length of the resistance coil wires which are guided about the rollers.

A still further object of our invention is the provision of an electric sadiron the rollers of which may be replaced by balls or similar bodies and which is comparatively simple in its construction, yet durable and highly efficient in use.

It is furthermore also one of the objects of our invention to provide an electric iron, the heating element of which is guided closely about the rollers in a novel and improved manner to positively heat the smoothing surface of the iron and its rollers, and thus greatly increase the efficiency of the iron.

These and other objects and advantages of our invention will become more fully known as the description thereof proceeds, and will then be specifically defined in the appended claims.

In the accompanying drawing forming a material part of this disclosure:

Fig. 1 is the side elevation of an electric flatiron constructed according to our invention, partly in section.

Fig. 2 is a bottom plan view of the same seen in the direction of the arrows on line 2—2 of Figure 1.

Fig. 3 is a cross-section on line 3—3 of Figure 1.

Fig. 4 is a bottom plan view of a modified form of our sadiron.

As illustrated in Figures 1 to 3, a flatiron of any well known type including its body 10 and handle 11 suitably connected to the body, and contact socket 12, has its bottom or ironing face 13 or plate provided with openings 14, 15 through which are visible the mantles or peripheries of rollers 16, 17 substantially flush with the bottom 13 of the iron. The rollers rotate on the shafts 18, 19 suitably journaled in bearings 21, 22 within the body of the iron, and adjustably held by means of the screws 23, 24 or the like. 20

The resistance wire or coil of the heating element 25 surrounds the rollers in close proximity to the same, and its terminals are connected in the well known manner to suitable contacts to be connected by a switch or plug entered into socket 12.

In the modified form of our invention illustrated in Figure 4, rollers 26, 27, 28 are of various sizes and are arranged in staggered relation to one another; they may evidently be replaced by 30 balls, casters or similar devices without departure from our invention. The resistance coil wire 29 also in this form surrounds the rollers in close proximity thereto in the body 30 of the iron.

The operation of our device will be entirely clear from the above description by simultaneously referring to the drawing, and it will be evident that the rollers with the smaller end of some of them and with the larger end of the other rollers mounted nearer to one side of the iron 40 than to the other side will thus produce a conical effect and will facilitate the guiding of the iron over a smooth surface and effectively flatten out all wrinkles, etc., so that even a child may be able to handle the iron; the heating element will allow 45 the use of current to develop the greatest possible amount of heat which in combination with the increased ironing surface will benefit the fabric to be ironed to the greatest extent.

It will be understood that we have disclosed 50 the preferred forms of our invention only as a few examples of the many possible ways to practically construct the same and that we may make such changes in the general arrangement of the iron and in the construction of its minor details 55

as come within the scope of the appended claims without departure from the spirit of our invention and the principles involved.

Having thus described our invention, what we claim as new, and desire to secure by Letters Patent, is:

- 5 1. An electric iron having openings in its bottom and comprising rollers of various sizes and located with the smaller ends of some of the rollers and with the larger end of the other rollers nearer to one side of the iron than to the other side for producing a conical effect, arranged in staggered relation to one another and extending into the openings in the bottom of the ironing

surface of the iron, and a heating element surrounding said rollers in close proximity thereto.

2. An electric iron having openings in its bottom and comprising a pair of tapered rollers with the smaller end of one of said rollers and the 5 larger end of the other roller mounted nearer to one side of the iron than to the other side and extending into the openings in the bottom of the ironing surface of the iron, and a heating element surrounding said rollers in close proximity 10 thereto.

ALFRED C. SCHMIDT.
CHARLES W. BRUGER.
